[57] CLAIM

The ornamental design for a cash drawer, as shown and described.

DESCRIPTION

FIG. 1 is a perspective view of a cash drawer showing my new design;

FIG. 2 is a side view thereof, the opposite side view being substantially identical;

FIG. 3 is a top plan view;

FIG. 4 is a bottom plan view thereof;

FIG. 5 is a front view thereof;

FIG. 6 is a rear view thereof, the portion shown in dashed lines forming no part of the design;

FIG. 7 is a perspective view of the cash drawer of FIG. 1 in an alternate open position; and,

FIG. 8 is a side view of the cash drawer in the alternate open position of FIG. 7, the opposite side view being substantially identical.
